UNITED STATES PATENT OFFICE.

LUDWIG DÜRR, OF FRIEDRICHSHAFEN, GERMANY, ASSIGNOR TO LUFTSCHIFFBAU ZEPPELIN GESELLSCHAFT MIT BESCHRÄNKTER HAFTUNG, OF FRIEDRICHSHAFEN, BODENSEE, GERMANY.

GAS-INFLATED AIRSHIP.

Application filed July 25, 1927, Serial No. 208,142, and in Germany August 23, 1926.

My invention relates to gas inflated airships and has special reference to such airships of this kind which are provided with a more or less rigid hull.

5 It is an object of my invention to facilitate the possibility of inspecting and watching the gas cells inserted in the hull of such ships. This inspection while on the ground and also when under way becomes of special 10 importance when two kinds of gases are contained in the hull. Lately it has been proposed to use a gaseous fuel for driving the 15 motors instead of gasoline, so that it will be necessary to provide for storage space for the fuel gas in addition to the gas space for the lifting gas. For this purpose it has been 20 designed to have two gas cells, one above the other, in a compartment of the airship's hull. Transverse members subdivide the hollow 25 inner hull space into such compartments. These transverse members generally are called rings and consist of a circumferential structure from rigid members stayed by inner braces forming a kind of bulkhead.

30 According to my invention the inner bracing of such rings which may be wire bracing for instance is so arranged that at a certain height from the bottom there are one or more crossing points adapted to support 35 loads. This means that the bracing is designed so that it may transmit forces resulting from such loads to the upper ring portions against which the lifting forces of the 40 lifting gas bear. To these crossing points are hung or otherwise fastened cat walk portions forming rigid structures reaching from 45 one bulkhead to another. At its forward and rear end this cat walk is connected to the hull structure. It will be advisable to 50 arrange the individual cat walk portions in their relative position so as to form one continuous element, but it is possible to shift one portion or another vertically or laterally, as circumstances may require. There may be one or more such cat walk portions inserted in one compartment. The length of one portion may be equal to the distance between two adjacent transverse ring members or it may extend over several compartments.

55 My cat walk construction may also be combined with the arrangement of some other longitudinal element, as for example, a rope running from the bow to the stern

through the airship's hull. Such a rope or 55 cable will also be fastened to the crossing point or points of the inner ring bracing which it meets.

Another main feature of my invention is the fact that the cat walk forming a longitudinal element within the hull does not 60 traverse the inner gas space of a gas cell but constitutes a connecting member between the inner bracings of two neighboring rings against which the walls of the gas cell or 65 gas cells can bear.

I prefer to arrange the cat walk at such vertical distance from the bottom of the airship hull that it traverses the compartment at about the plane where the upper and the 70 lower gas cells meet. In one of the rings stairs or the like may be provided for the purpose of getting access to the cat walk from below where the usual longitudinal 75 keel structure or gang way may have its place.

Such cat walk between the two gas cells affords the desired opportunity of inspecting the gas cells especially with regard to 80 their state of inflation and of watching their walls as to the occurrence of rips, holes or the like. It may be advisable to provide for a kind of rope crane or the like connecting the cat walk structure to an adequate longitudinal element at the inner circumference 85 of the hull, or a kind of net may be provided between the walls of the gas cells. Such rope or net will serve for further facilitating the possibility of inspecting the 90 gas cell walls.

The cross section of the cat walk structure may be of any shape but it should be so that the structure is safe against compression 95 stresses which may turn up in case the respective compartment should run empty from gas inflation, when the neighboring gas cells will tend to bulge into the empty compartment pressing against the adjacent ring bracings which are to be held at a constant 100 distance from each other by means of my cat walk structure.

The crossing points of the ring bracing to which the cat walk structure is fastened according to my invention may serve also for hanging other loads to them, as for example, 105 cars, ballast or fuel containers, and the like. The cat walk portion within a compartment or extending over several compartments may

be fastened to the crossing points directly or it may be suspended therefrom by means of cables or the like in the manner of a suspension bridge.

5 It will be advantageous to make use of my cat walk construction also for the purpose of supporting the lines necessary for the inflation of the gas cells with lifting gas, the lines for transporting the fuel for the 10 motors to their containers, be the fuel of liquid or gaseous character, and the lines for distributing the ballast over the length of the airship. This arrangement allows for 15 convenient connections to the storing places and the forward ends of the lines should extend to the bow of the ship, possibly to a mooring point, thus allowing for easy connection to corresponding lines on the ground when the ship is moored, for instance to a 20 mooring mast equipped with gas, fuel and ballast connections.

Having given a general description of my invention I now want to point it out more in detail referring to the drawings which 25 represent examples embodying my invention.

Fig. 1 is a diagrammatical longitudinal section through an airship. Fig. 2 is a cross-sectional view illustrating one of the transverse rings of the airship. Figs. 3, 4 and 5 are cross sections through the airship but representing different examples of the cat walk and the gas cell arrangement.

The hull of the airship is made up of rings 30 *a* and longitudinal girders *b*. Especially referring to Fig. 2, the crossing points of the ring bracing are designated by the letter *c*. At these points *c* the cat walk portions *d* are suspended. There may be provided only one crossing point in a ring bracing or a plurality of them. In the example represented in Fig. 2 two crossing points are shown, whereas in the example of Fig. 5 one point is thought sufficient. By means of 45 cables *e* a motor car *f* also is suspended from points *c*. Ballast containers *g* and fuel containers *h* may be suspended from points *c* also and in like manner.

The ends of the cat walk formed by the 50 individual portions are connected to the frame work of the hull as may be seen from Fig. 1. The cat walk portions in the forward part of the airship are constructed like girders whereas the portions in the rear are 55 designed in a suspension bridge manner. In both cases the crossing points *c* in the different rings *a* are in direct connection by means of a longitudinal member *i* which may form the upper element of the cat walk structure. Lines *k* are provided within the 60 cat walk and serve for the purposes described above. The usual gangway *l* runs longitudinally of the bottom of the hull.

In Fig. 3 the arrangement of a single gas 65 cell in one compartment of the hull in com-

bination with the cat walk is represented. In Fig. 4 an upper lifting gas cell *m* and a lower fuel gas cell *n* is shown. The same gas cell arrangement applies to Fig. 5, only the cat walk has a triangular cross section in 70 contradistinction to the other figures in which its cross section is of rectangular shape. Between the adjacent walls of cell *m* and cell *n* a network *o* or the like is provided which is supported at one side by the 75 cat walk structure *d* and at the other by longitudinal girders *p*.

I do not want to be limited to the details described or shown in the drawings as many variations will occur to those skilled in the 20 art.

What I claim is:

1. An airship comprising a hull made up of longitudinal members and of braced rings, 85 said ring bracings each having a crossing point adapted for suspending loads therefrom; and cat walk portions each extending from one of said rings to another one, said portions being suspended from said crossing points of said ring bracing. 90

2. An airship comprising a hull made up of longitudinal members and of braced rings, 95 said ring bracings each having a crossing point adapted for suspending loads therefrom; and cat walk portions each extending from one of said rings to another one, said portions being suspended from said crossing points of said ring bracing; and two terminal cat walk portions extending from the foremost and from the rearmost of said 100 rings, respectively, to the bow and stern of said airship, respectively.

3. An airship comprising a hull made up of longitudinal circumferential members and of braced rings, said rings subdividing 105 said hull into compartments, a rigid member inside of one of said compartments and extending substantially in the longitudinal direction of said airship, said rigid member being independent of and spaced apart 110 from, said longitudinal members connecting corresponding points in the bracing of those two of said rings which form the end walls of said one compartment.

4. An airship comprising a hull made up 115 of longitudinal circumferential members and of transverse rings having an inner bracing, said rings subdividing said hull into compartments, a rigid member inside of each of said compartments and extending 120 longitudinally of said airship, said rigid members connecting corresponding crossing points of said inner ring bracings, the members in the bow and stern compartments, respectively, with one end connecting to said 125 outer hull structure.

5. An airship comprising a hull made up of longitudinal circumferential members and of transverse rings having an inner bracing, said rings subdividing said hull 130

- into compartments, a rigid member inside of each of said compartments and extending longitudinally of said airship, said rigid members connecting corresponding crossing 5 points of said inner ring bracings, the members in the bow and stern compartments, respectively, with one end connecting to said outer hull structure; all said inner rigid members together constituting one continuous 10 cat walk from the bow to the stern of said airship.
6. An airship comprising a hull made up of longitudinal circumferential members and of transverse rings having an inner 15 bracing, said rings subdividing said hull into compartments, a rigid member inside of each of said compartments and extending longitudinally of said airship, said rigid members connecting corresponding crossing 20 points of said inner ring bracings, the members in the bow and stern compartments, respectively, with one end connecting to said outer hull structure; all said inner rigid members together constituting one continuous 25 cat walk from the bow to the stern of said airship, the bow end of said cat walk forming a mooring point for said airship.
7. An airship comprising a hull made up of circumferential longitudinal members and of transverse rings having an inner 30 bracing, said bracings having special crossing points adapted to have loads suspended therefrom; and a plurality of suspension-bridge-like structures, said structures being 35 connected to said crossing points.
8. An airship comprising a hull, said hull comprising a transverse ring member having an inner bracing, said bracing having a special crossing point, and loads such as 40 cars, fuel, ballast and the like being suspended from said crossing point.
9. An airship comprising a hull, said hull comprising a transverse ring member having an inner bracing, said bracing having a special crossing point; an inner cat walk 45 structure suspended with one end from said crossing point.
10. An airship comprising a hull, said hull comprising a transverse ring member having an inner bracing, said bracing having a special crossing point; an inner cat walk structure suspended with one end from said crossing point; and loads such as cars, fuel, ballast and the like being also suspended 50 from said crossing point.
11. An airship comprising a hull made up of circumferential longitudinal members and of transverse rings with inner bracing; said rings subdividing said hull into compartments; one of said compartments enclosing 60 an upper and a lower gas cell; and an inner longitudinal member arranged in said compartment between said two gas cells, said member being suspended from and connected to said bracing of those two of said rings 65 which form the ends of said one compartment.
12. An airship comprising a hull made up of circumferential longitudinal members and of transverse rings with inner bracing; 70 said rings subdividing said hull into compartments; one of said compartments enclosing an upper and a lower gas cell; an inner longitudinal member arranged in said compartment between said two gas cells, said 75 member being suspended from and connected to said bracing of those two of said rings which form the ends of said one compartment; and means for inspecting the adjacent walls of said two gas cells, said means 80 being supported partly by said inner longitudinal member, partly by one of said circumferential longitudinal members.

LUDWIG DÜRR.
